COMBINED TOE SOCK AND TONGUE FOR WEAR WITH BOOTS

Michael W. Marriner, 3009 Bern Drive,
Laguna Beach, Calif. 92651

Filed Aug. 12, 1974, Ser. No. 496,563

Term of patent 14 years

Int. Cl. D2—04

U.S. Cl. D2—330

FIG. 1

FIG. 2

FIG. 3

FIG. 4

FIG. 5

FIG. 6

FIG. 1 is an isometric view of a combined toe sock and tongue for wear with boots showing my new design;

FIG. 2 is a view in side elevation thereof;

FIG. 3 is a bottom plan view thereof;

FIG. 4 is a top plan view thereof;

FIG. 5 is a view in end elevation thereof; and

FIG. 6 is a view in front elevation thereof.

I claim:

The ornamental design for a combined toe sock and tongue for wear with boots, as shown.
